VEHICLE DOOR CONSTRUCTION

George Trautvetter, Philadelphia, Pa., assignor
to Edward G. Budd Manufacturing Company,
Philadelphia, Pa., a Corporation of Pennsyl-
vania

Application January 16, 1932. Serial No. 586,998

3 Claims. (Cl. 296—44)

The invention relates to vehicle body doors and more particularly to such doors built up out of sheet metal.

It is an object of the present invention to simplify the construction of such doors particularly in the region adjoining a window opening therein, to make the parts more readily adaptable for assembly and to provide a door structure of this class having increased strength 10 and durability and a neater and more finished appearance than has heretofore been attained.

These objects I have in a large degree attained by the construction shown in the accompanying drawing illustrating a preferred embodiment of 15 my invention.

In the drawing,

Fig. 1 is an inside perspective of an outer panel stamping according to the invention.

Fig. 2 is an enlarged fragmentary perspective view, parts being shown in section, showing the construction of a vertical door rail at the side of the window opening.

Fig. 3 is a similar view at an upper corner of the door showing the top rail in section.

25 In the drawing the invention has been shown applied to a door built up principally of outer and inner panel stampings, such as is shown, for example, in my prior application Serial No. 421,374, filed January 17, 1930 for pressed metal doors, but it will be understood that certain features thereof are applicable whether the door involves the use of a one piece inner panel extending entirely around the window opening or not.

35 According to my invention the outer panel 10 is formed as a one piece stamping having edge flanges 11 adapted in the final assembly to be crimped around the edge flanges 12 of the inner frame panel 13 and spot welded thereto. The side and top rails of the door are shown as forming portions of an inner panel stamping 14 also extending entirely around the window opening.

45 The side and top rails surrounding the window openings are shown as comprising generally transversely extending portions 15 forming the door jamb, and outer laterally extending edge flanges 12, about which the outer panel edges are crimped as already described. In the present instance this transverse jamb portion is shown provided with an offset, to fit against a corresponding offset in the door frame, but it will be understood that this invention is equally applicable to door jambs not provided with such an offset.

The inner panel in the sides and top of the window opening has this jamb portion 15 reversely bent to provide moulding around the window opening, and providing a transversely extending portion 16 of less width than the 60 width of the jamb face portion 15 spaced from the latter and providing a seat against which may be secured a removable moulding, not shown, for retaining and guiding the window.

The outer panel 10 is turned in around the 65 window opening at 17 to provide moulding and at sides and top this inturned portion 17 is extended by a flange 18 of double angle form including a portion 19 extending toward the jamb and forming the outer wall of the glass run, a 70 portion 20 extending transversely inwardly and forming the bottom of the glass run, a portion 21 extending to the jamb portion 15 of the inner panel, and a portion 22 overlapping the jamb portion 15.

75 The edge of the inner panel portion 16 is in substantially the plane of the portion 21 of the outer panel and its edge overlaps the inner edge of the portion 20 and is secured thereto by spot welding. Preferably in order to localize the 80 heat and facilitate the weld the outer panel portion is formed in the overlap with spuds 22 which are melted down by the heat of the weld, leaving the parts seated flush in engagement with each other as shown. The portion 20 may 85 also be provided with a shallow offset 23 of the thickness of the inner panel to receive the edge of the inner panel, thus leaving a smooth flat transverse surface from the inside of the opening to the outer side wall 19 of the glass run. 90

95 The portion 21 forms a rigid brace between the portion 16 and the jamb portion 15, permitting the welds to be made by having the electrodes engage, respectively, the outside of the jamb portion 15 and the inside of the portion 16 without danger of collapse of the parts toward each other under the pressure exerted by the electrodes, and also furnishing additional strength to the rail in the final assembly.

100 The overlapping edge flange 22 of the outer panel is preferably spot welded to the jamb portion 15 of the inner panel to further stiffen and brace the structure and prevent squeaks due to relative movement of engaging metal parts, and this spot welding is preferably carried out prior to the attachment of the edge of the inner panel portion 16 to the portion 20 of the outer panel to insure greater rigidity during the welding of these parts. Access is 105 provided for directly spot welding the flange 22. 110

to the jamb portion 15 through spaced openings, as 24, provided at suitable distances in the transverse portion 16 of the inner panel. Spuds 25 are provided on part 16 to facilitate the weld and to minimize weld marks.

5 From the foregoing description of the construction and method of assembly of the improved door it will be seen that I have provided a very strong rigid and durable construction of door rail, and a construction in which the parts are well adapted for ready assembly by spot welding and also one in which a neat and finished appearance is preserved in a very high degree.

10 The features by which these advantages are attained may be modified within the skill of one skilled in the art, without departing from the spirit and scope of the invention as expressed in the claims appended hereto.

15 What I claim is:

20 1. A metal widow rail construction built up of inner and outer stampings, the inner stamping having a transverse web portion forming the jamb portion of a door and its inner edge reversely bent, the reversely bent portion being spaced from the transverse web portion, the outer panel stamping being formed along one margin of double angular form, the reverse bent portion of the inner panel overlapping and secured to an intermediate portion of said double angular margin, and the edge of the outer panel secured to said jamb portion of the inner panel, openings being provided in the reversely bent portion of the inner stamping to permit access 25 of a tool for securing the edge of the outer stamping to the jamb portion of the inner stamping.

2. A metal window rail construction comprising an inner panel having a transversely extending web portion forming the jamb portion of a door and having its inner edge reversely bent, the reversely bent portion being spaced from said jamb portion, and a stepped glass run channel member comprising a portion of double angular form, the one angle forming the outer side and bottom of the glass run, the portion forming the bottom of the glass run being offset along its inner margin to approximately the thickness of the metal of the inner panel the reversely bent portion of the inner panel overlapping and secured to the offset portion of said member forming the bottom of the glass run, and supported in spaced relation from the jamb face portion by the other angle of said double angular member.

3. A metal window rail construction comprising a reversely bent inner panel providing spaced transversely extending portions, one of greater width forming the jamb face of the door and the other of lesser width forming a seat for removable window moulding, and an outer panel having its inner margin formed of double angular form providing a stepped formation, one step forming the bottom of a glass run, the margin of said lesser width portion of the inner panel being spot welded to said step, and the bottom of the other step being spot welded to the jamb face portion of said inner panel, openings being provided in the lesser width portion to permit access of the welding electrode.
